DRAWBENCH

Earl Knudsen and Howard H. Talbot, Pittsburgh,
Pa.; said Talbot assignor to United Engineering
& Foundry Company, Pittsburgh, Pa., a cor-
poration of Pennsylvania

Application March 7, 1944, Serial No. 525,396

12 Claims. (Cl. 205—3)

This invention relates to draw-benches, and more particularly to those for reducing or shaping simultaneously a plurality of elongated blanks, such as tubes, rods, bars, or other shapes.

It is among the objects of this invention to provide a draw-bench which can be mounted at floor level, which is relatively low in height, which requires no pit for accommodating any part of it, which releases all of the drawn blanks from the same side of the machine, which cannot be fouled by broken blanks, and in which a drawing carriage is automatically returned to the die by one path while a plurality of carriages are simultaneously drawing blanks along another path.

In accordance with this invention a blank-gripping carriage, which initially is located in front of a die, is detachably engaged from above by means that moves the carriage with a blank which it is gripping forward away from the die to a position in which the blank is released from the die and carriage and drops down away from them upon skids or transverse conveyors. The released carriage is then transferred to a return track, preferably above the drawing path, on which it is returned to a position adjacent the die. At that point means are provided for transferring the carriage to operative or blank-gripping position in front of the die so that the drawing cycle can be repeated. Preferably, the means by which the carriage is moved away from the die consists of an endless chain the lower reach of which engages a hook on the carriage to pull it along a track. After a blank has been drawn, the carriage may be raised by an elevator to the front end of the return track on which the carriage is returned by the upper reach of the chain to a position above the die. At the rear end of the track the carriage may be lowered by an elevator to its original position in front of the die. By using several carriages with their blank-gripping jaws located in different positions, two or more longitudinally spaced carriages can draw blanks through a plurality of dies at the same time in overlapping succession, thereby making the drawing process continuous.

The preferred embodiment of the invention is illustrated in the accompanying drawings in which Figs. 1 and 2 are plan views of opposite end portions of my draw-bench; Figs. 3 and 4 show the end portions in elevation; Fig. 5 is an enlarged vertical section showing a carriage in section on the lower track and the front end of another carriage on the upper track; Fig. 6 is a fragmentary vertical section showing the front

end of a carriage located in blank-gripping position in front of the dies; Fig. 7 is an enlarged fragmentary side view of the mechanism by which the carriages are hooked onto the chain; Fig. 8 is a view similar to Fig. 7 but showing the carriage hook-actuating means that are behind the hooking mechanism of Fig. 7; Fig. 9 shows the carriage hook as it first engages the chain; Fig. 10 is a vertical longitudinal section through the carriage in front of the dies; Fig. 11 is a bottom view of the carriage with the hook swung up into chain-engaging position; Fig. 12 is an enlarged plan view of the elevator at the front end of the track; Fig. 13 is an enlarged fragmentary side view of the same elevator; Fig. 14 is an enlarged view of the carriage shown in Fig. 10; and Fig. 15 is an enlarged fragmentary front view of the die support showing the arrangement of the dies therein.

Referring to Figs. 1 to 5 and Fig. 15 of the drawings, a plurality of dies 1 are mounted in the upright front end of a support 2 fastened to the floor. Starting at a point spaced a short distance in front of the dies there is a horizontal drawing track consisting principally of a pair of H-beams 3 supported from above by cross members 4 that are connected at one end to vertical columns 5 at one side of the track. These columns are held in upright position by means of long horizontal feet 6 connected to their lower ends and resting on the floor underneath the track. The feet project from the side of the track opposite the columns. Diagonal bracing members 7 (Fig. 5) connect these feet with the columns and also support wooden strips 8 that form skids for drawn blanks that fall upon them. The blanks roll or slide down the skids and onto the end portions of the feet projecting beyond the side of the track where the blanks may be conveniently picked up by a crane or other lifting device. Or, if desired, the blanks may roll from the skids onto an endless conveyor traveling lengthwise of the track. The drawing track is spaced from die support 2 by a pair of heavy bars 9 secured to the outer surfaces of the webs of H-beams 3 and to the front of the die support. Among other things, these bars prevent the track and die support from being moved toward each other during the drawing operation.

Connected to the lower surfaces of the upper inner flanges of H-beams 3 are wide plates 11, as shown in Figs. 5 to 7, that extend substantially the full length of the H-beams. The lower strand or reach of an endless chain 12 extends lengthwise of the drawing track between the H-beams,

and alternate links are provided above with outwardly projecting flanges 13 that slide along the top of the two plates 11 and thereby suspend the chain links below the plates. A standard chain can be used (without flanges 13) by merely mounting plates 11 vertically on opposite sides of the chain and bending their lower edges inwardly to support it. The chain extends around a drive sprocket 14 at the front end of the track, and around a wheel 15 journaled in bearings 16 mounted on the rear end of the track in front of the dies. The drive sprocket is driven from one side of the track through a gear reduction unit 17 (Fig. 2) that is operated by a motor 18 in front of the track. The drive sprocket is spaced from the front of the track by a spacing member 19 which forms with the track and bars 9 a strut between the drive and die support 2. This strut takes the pulling stresses so that the unit is self-contained and does not have to depend upon the foundation or floor.

The upper strand of the chain is supported for most of its length by a channel 20 mounted on cross members 21 above the drawing track. These cross members are supported by vertical angle irons 22 projecting upwardly from the track. The upper ends of these angles support a return track consisting of a pair of spaced parallel Z-bars 23 of substantially the same length as the lower track.

The lower track is adapted to receive and guide a plurality of tube-gripping carriages 25, each comprising a frame 26 having a pair of vertical wheels 27 near each end that travel on rails 28 mounted on the lower inner flanges of H-beams 3, and horizontal wheels 29 that roll against the sides of the rails to center the carriage in the track. The wheels also confine the carriage to its path and take the off-center pull on it. As shown in Figs. 5, 10, 11, and 14, the carriage frame is provided under its rear end with an integral cross head 31 having longitudinally extending open-bottom openings 32 through its opposite ends in line with two of the dies. Each of these openings tapers in a horizontal plane toward its rear end and slidably receives and guides a pair of blank-gripping jaws 33 the front ends of which are provided with hooks that hook under the downwardly projecting rear ends of slides 34 on the bottom of the carriage frame. The two slides each have a pair of transverse ribs 35 between which the rounded ends of a cross arm 37 are disposed. The center of the cross arm is pivotally supported from a plate 38 that is slidably connected to the bottom of the carriage frame. The front end of this plate has a downwardly projecting portion which is pivotally connected by links 39 to the lower end of a normally inclined forked lever 40. The forks of this lever extend upwardly and rearwardly with their middle portions pivotally connected to the sides of a block 41 which is reciprocable lengthwise of the carriage in downwardly projecting guide members 42.

This block normally is held in its rear position by means of a coil spring 44 encircling a bolt 45 screwed into the rear end of the block and projecting slidably into a cylindrical chamber 46 in the carriage frame. The spring is compressed between the front wall of this cylinder and the head of the bolt. As shown in Fig. 10, the front of the block bears against a plunger 47 projecting from a dashpot cylinder 48 mounted in the carriage frame. A piston 49 is mounted on the plunger in the cylinder the front end of which is

provided with a forwardly extending passage 50 in which the front end portion of the plunger is slidably mounted. This portion of the plunger is provided in its surface with a longitudinal groove 51 that tapers from its front end toward the piston. The front end of the cylinder is connected by a vertical opening 52 with the front end of another cylinder 53 suspended below the frame and in which a piston 54 normally is maintained in a forward position by a coil spring 55 compressed between it and the back end of the cylinder. When the plunger is pushed forward in the upper cylinder the fluid in front of the piston escapes slowly through plunger groove 51 and into passage 50 from which it flows into the lower cylinder. As piston 49 approaches the front of the upper cylinder it is retarded because the cross section of the groove is diminishing in size and thereby gradually restricting the discharge of liquid. The liquid entering the lower cylinder pushes the piston therein rearwardly against the resistance of spring 55. When the plunger is released, the spring in the lower cylinder pushes the lower piston forward which forces the liquid out through a ball check valve 56 that connects vertical opening 52 with the inside of the upper cylinder, thereby forcing upper piston 49 back to its original position.

The upper ends of the forks of lever 40 are pivotally connected by a pair of links 58 to the bifurcated upper end of a hook 59 that hangs down from the front of the carriage frame. The hook is supported by rollers 60 that are carried by the links in horizontal guideways 61 in the inner faces of two forwardly projecting extensions 62 of the carriage frame, as shown in Figs. 6, 10, and 11. The rollers are movable along these guideways. The rear ends of the links are connected by coil springs 63 (Fig. 10) to the rear end of the carriage frame so that the links normally are held in their rear position.

When a carriage is in position ready to grip blanks 65, such as tubes or rods, projecting through the dies, it is supported in front of the dies in line with the rear end of the lower track by an elevator that will be described later. In this position the blanks, which have had their front ends forged down, are pushed through two of the dies that are on the level of carriage cross head 31 and between jaws 33 in the openings thereof. Hook 59 is then swung upwardly, as shown in Fig. 9, so that it will be engaged by one of the links of the chain as it travels down around chain-supporting wheel 15. As this link engages the hook and moves forward it pulls the hook forward between the carriage frame extensions 62 to the position shown in Fig. 3, and thereby, through links 58, it swings the upper end of forked lever 40 forward on its pivot in block 41. This swings the lower end of the lever rearwardly to move back the cross arm 37 and the jaws which are operatively connected thereto. As the jaws move back in the wedge-shaped openings 32 in the cross head, they clamp onto the blanks. The inertia of the carriage will generally be sufficient to hold it substantially stationary when the hook is first engaged by the chain so that the jaws will be moved backwardly in the carriage. If desired, however, positive means, such as a magnet 66 (Fig. 10) may be mounted in die support 2 for the purpose of initially restraining forward movement of the carriage. Continued travel of the chain after the blanks have been gripped in this manner causes the forked lever, the lower end of which can swing back no farther,

to move block 41 forward in its guides 42 against the cushioning resistance of the dashpot. The dashpot relieves the shock that otherwise would occur when the chain starts to pull the carriage away from the die support; that is, on account of the dashpot, the carriage starts to move forward slowly while the liquid is being forced out of the front of the dashpot cylinder 48.

In order to swing the hook up into engagement with the chain, a mechanism is provided for that purpose which is under the manual control of the operator. As shown in Figs. 6 and 7, this mechanism comprises a lever 70 that is pivotally mounted on the side of one of the bars 9 at the rear end of the track. The upper end of this lever is pivotally connected by a link 71 to a block 72 which is slidably horizontally in a guide member 73 mounted on top of the adjacent H-beam 3. The block is reciprocated by a piston and cylinder 74 also mounted on the H-beam in front of the guide member. The lower end of the lever has a rearward extension with an inwardly projecting lug 75 at its outer end in which a horizontal bolt 76 is slidably mounted. The front of this bolt is pivotally connected to the back of a vertical shoe 77, and a coil spring 78 is compressed between lug 75 and the front end of the bolt. The lower end of the shoe is pivotally mounted on a pin 79 projecting from the inside of the lower end of lever 70. This shoe is adapted to yieldingly engage a roller 81 on the lower end of an arm 82 which is pivotally connected to the outside of the carriage frame. As shown in Figs. 6, 8 and 11, the upper end of this arm is rigidly connected underneath the carriage frame to the upper end of a toggle link 83 the lower end of which is pivotally connected to the lower end of the other link 84 of the toggle. The upper end of the second link is pivoted to one side of hook 59, so that when the lower end of hooking lever 70 is swung forward as shown in Fig. 9, the shoe 77 carried by it engages roller 81 and swings the arm 82 forward to thereby straighten the toggle which thus causes the hook to be swung upwardly into chain-engaging position. To assure that the hook will not drop away from the chain before it is time to do so, the upper end of arm 81 is provided with a shoulder 85 that is engaged by a spring-pressed pawl 86 on the side of the carriage when the arm is swung forward.

Before the carriage reaches the front end of the lower track the rear ends of the blanks being drawn by it leave the dies and drop down onto the inclined skids below the track. This releases the tension on jaws 33 so that the front ends of the blanks fall away from the carriage. Thereafter, pawl 86 strikes an adjustable trip 87 on the track and is released from shoulder 85 to permit the hook to fall away from the chain and to be retracted into the carriage by springs 88. The carriage continues to be moved forward by the chain, due to engagement of a chain link with a slightly resilient member 88 attached to the top of the carriage and projecting above it, until the carriage is on the downwardly inclined front end of the track from which it rolls onto an elevator that is there waiting for it, as shown in Figs. 2, 4, 12 and 13.

This elevator is formed from a pair of spaced parallel angle irons 90 the rear ends of which rest on brackets 91 attached to the front of the track so as to form a continuation of the track for receiving the carriage. These angles are rigidly connected together by a central yoke 92 above them. On top of this yoke there is an

integral bearing 93 oscillatably mounted on a horizontal pin 94 projecting from a support 95 the outer end of which is slidably vertically in a guideway in one side of a post 96 located at one side of the track. This sliding support is raised and lowered by means of a cable 97 extending from its top up over a pair of vertical pulleys 98 rotatably connected to a bracket 99 on the front of the post. The cable then passes down under a pulley 101 mounted at the bottom of the post, and then horizontally under the track to a block 102 which is slidably mounted in a horizontal guide 103. This block is reciprocated in the guide by means of a horizontal piston and cylinder 104 rigidly mounted below the track. To limit tilting of the elevator on pin 94, its support 95 is provided with a pair of laterally projecting arms 105 both of which are spaced a short distance above the top of the yoke when the elevator is level. One or the other of these arms is engaged by the yoke after it has tilted a predetermined distance in either direction. The reason for permitting the elevator to tilt is to allow it to incline itself in one direction in front of the lower track for receiving a carriage, and in the opposite direction in front of the upper track (as indicated by broken lines in Fig. 4) so that the carriage will roll off the elevator and onto the upper track. Tilting of the raised elevator is caused by its rear end striking the bottom of a pair of brackets 106 fastened to the front of the upper track.

As the carriage rolls down the slightly inclined front end of the upper track its depending hook 59 passes over the top of a short length of chain 12 without touching it, because that portion of the chain is allowed to sag in the space between the drive sprocket and the front end of channel 20. This makes it possible to stop the carriage in case an emergency arises which requires the return of the carriage to the rear end of the track to be delayed. The carriage may be stopped in this emergency stop area by any suitable means, such as by a fluid pressure actuated stop device 107 mounted on top of the upper track. Unless this device is actuated, the carriage will continue to roll back along the top track until a downwardly projecting point 108 on the carriage hook is engaged by a link of the upper strand of the chain supported by channel 20. After this engagement the chain pushes the carriage rearwardly on the top track until it is near the end of the track.

Near their rear ends, both the top track and the upper strand of the chain are inclined upwardly for a short distance, and then downwardly the rest of the way as shown in Fig. 3. This gives a downwardly inclined section of the track at the rear end which permits the carriage to roll by gravity after the chain has fallen away from its hook. The carriage normally is prevented from rolling off the rear end of the top track by an escapement lever 110 pivotally mounted above the track on a cross beam 111. Near the rear end of this lever there is a downward projection 112 that is engaged by the carriage to stop it. The front end of the lever has a similar projection 113 which will stop the next carriage when the rear end of the lever is raised to release the first carriage. When this first carriage is released by the escapement lever it rolls onto a slightly inclined elevator that is there to receive it. The position of the raised elevator is indicated by broken lines in Fig. 3.

This elevator is in the form of a horizontal plate 115 having parallel vertical sides from the lower edges of which flanges 116 project inwardly

toward each other and form continuations of the track with which they happen to be aligned. The top of the elevator is provided with an integral bearing 117 oscillatably mounted on a horizontal pin 118 projecting from a support 119 at one side of the elevator. The outer end of this support is slidable vertically in a guideway in the side of a post 120 rigidly mounted beside the track. The sliding support is reciprocated by a vertical rod 121 connected to its bottom, as shown in Fig. 3. The lower end of this rod is pivotally connected to the front end of a roughly triangular lever 122 the upper corner of which is pivotally connected to the inside of die support 2. The rear end or third corner of this lever is pivotally connected by a link 123 to a block 124 slidably mounted in a guide member 125 mounted on the floor beneath the track. This block is reciprocated by a horizontal piston and cylinder 126 also rigidly mounted on the floor and spaced from the die support by a pair of rods 127.

Due to the location of bearings 117 on plate 118, the rear end of the elevator tends to swing downwardly, but the elevator normally is maintained level by a coil spring 130 on a vertical bolt 131, as shown in Fig. 8. The bolt extends down through an enlarged opening in an arm 132 projecting laterally from pin support 119, and the lower end of the bolt is rigidly connected to the top of the elevator. The coil spring is compressed between the head of the bolt and arm 132. This spring does not prevent the elevator from being tilted by a stop 133 on the post when raised to its upper position at the end of the top track. When the elevator is raised, bearing 117 strikes the projecting rear end of escapement lever 110 and swings it upwardly to release the carriage that it has been holding on the top track. The carriage rolls onto the elevator while the one behind it is arrested by the front end of the lever.

In its lower position the elevator is disposed between the two bars 9 at the rear of the lower track of which the elevator then forms an extension. Downward movement of the elevator is limited by a pair of lugs 135 that project from its opposite sides onto the top of the two bars. To prevent the rear end of the elevator from kicking up when the chain starts to pull the carriage forward, it is engaged by a latch 136 that is pivotally supported by a bearing 137 mounted on one of the bars. As shown in Fig. 7, the latch is swung into operative position by means of a spring 138 connected to the bar and to a crank arm 139 attached at its upper end to the latch. The latch is removed from the elevator by means of a longitudinally movable wedge 141 that is actuated by a fluid pressure cylinder 142 connected to the side of the bar. The wedge slides along the side of the bar in engagement with a roller 143 on the lower end of arm 139. If it is found desirable, another similar latch mechanism may be mounted on the opposite side of the elevator.

As shown in Fig. 3, a carriage that is connected to a pair of blanks is being pulled along the lower track, while another carriage is positioned in front of the dies ready to grip a second pair of blanks also extending through the dies. After the lower blanks have left the dies, and before the upper blanks likewise have been released, a third carriage on the rear end of the upper track will be lowered into position in front of the dies for drawing the next pair of blanks through the lower dies, thereby keeping the process continuous. This is possible because the lower set of dies is located between the upper pair, and the

cross head 31 of every other carriage is short enough and extends downwardly far enough to enable it to pass down between the upper pair of blanks and position its gripping jaws in front of the lower set of dies. The difference in length and depth of the cross heads on alternate carriages is illustrated in Fig. 5, as well as in Figs. 3 and 4.

A draw-bench constructed in accordance with this invention has the advantage that all of the drawn blanks can be removed from the same side of the machine. Also, by having the carriages grip the blanks from above, the latter can not accidentally fall into the chain and foul the machine. As the drawing track is located below the return track, the draw-bench does not require a pit and therefore can even be located on the second floor of a building. It likewise does not require much head room. The lower strand of the endless chain passes through the carriage, and the pivot of the carriage hook is on the same level as that strand, whereby the chain exerts a straight ahead pull on the carriage with no buckling of the chain. Due to the carriages returning to the dies by a different path than the one in which they are pulled away, no time is lost in returning the carriages, and the drawing operation can be kept continuous.

According to the provisions of the patent statutes, we have explained the principle and operation of our invention and have illustrated and described what we now consider to represent its best embodiment. However, we desire to have it understood that, within the scope of the appended claims, the invention may be practiced otherwise than as specifically illustrated and described.

We claim:

1. A draw-bench comprising a blank-gripping carriage adapted to be positioned in front of a die, endless traveling means extending forward away from the die and having a lower reach for detachably engaging the carriage from above to move it with a gripped blank forward away from the die to a position at which the blank is released from the die and carriage and drops down away from them, a return track above the upper reach of said means, means for elevating the released carriage from said lower reach to the front end of said track, and means for lowering the carriage from the rear end of the return track to blank-gripping position in front of the die.

2. A draw-bench comprising a blank-gripping carriage adapted to be positioned in front of a die, an endless chain extending forward away from the die and having a lower strand for detachably engaging the carriage from above to move it with a gripped blank forward away from the die to a position at which the blank is released from the die and carriage and drops down away from them, a return track above the upper strand of said chain, means for elevating the released carriage from said lower strand to the front end of said track, the upper strand of the chain being adapted to return the carriage along said track, and means for lowering the returned carriage from the rear end of the return track to blank-gripping position in front of the die.

3. A draw-bench comprising a blank-gripping carriage adapted to be positioned in front of a die, endless traveling means extending forward away from the die and having a lower reach, said carriage being provided with a connecting member adapted to be detachably engaged from above by said lower reach to move the carriage with a gripped blank forward away from the die to a position at which the blank is released from

the die and carriage and drops down away from them, a return track above the upper reach of said means, means for elevating the released carriage from said lower reach to the front end of said track, the upper reach of said endless means being adapted to detachably engage said connecting member to return the carriage along said track, and means for lowering the returned carriage from the rear end of the return track to blank-gripping position in front of the die.

4. A draw-bench comprising a blank-gripping carriage adapted to be positioned in front of a die, endless traveling means extending forward away from the die and having a lower reach, said carriage being provided with a normally depending hook pivoted on a horizontal axis, means for swinging the hook up into engagement with said lower reach whereby the carriage is pulled forward away from the die to a position at which the blank is released from the die and drops down away from them, said hook falling away from said lower reach when the carriage is released, a return track above the upper reach of said means, means for elevating the released carriage from said lower reach to the front end of said track, the upper reach of said endless means being adapted to engage the depending hook of the carriage to return the carriage along said track, and means for lowering the returned carriage from the rear end of the return track to blank-gripping position in front of the die.

5. A draw-bench comprising a blank-gripping carriage adapted to be positioned in front of a die, a drawing track extending forward from the die and having a downwardly inclined front end, a return track above the drawing track and having a downwardly inclined rear end, endless traveling means having a lower reach for detachably engaging the carriage from above to move it with a gripped blank forward along said drawing track to a position at which the blank is released from the die and carriage and drops down away from them, an elevator for raising the released carriage from said drawing track to the front end of the return track, the upper reach of said endless means being adapted to return the carriage along the return track, an elevator for lowering the returned carriage from the rear end of the return track to blank-gripping position in front of the die, and means for tilting said elevators longitudinally to align them with the inclined front and rear ends of the return track.

6. A draw-bench comprising a blank-gripping carriage adapted to be positioned in front of a die, means for detachably engaging the carriage from above to move it with a gripped blank forward away from the die to a position at which the blank is released from the die and carriage and drops down away from them, a return track above said means, means for elevating the released carriage from said carriage-engaging means to the front end of said track, means for temporarily stopping the elevator at the rear end of the return track, an elevator that releases said stopping means when the elevator is raised to carriage-receiving position at the rear end of the return track, and means for lowering the elevator to lower the carriage to blank-gripping position in front of the die.

7. A draw-bench comprising a blank-gripping carriage adapted to be positioned in front of a die, a drawing track extending forward from the die and having a downwardly inclined front end, a return track above the drawing track and having a downwardly inclined rear end, endless traveling

means having a lower reach for detachably engaging the carriage from above to move it with a gripped blank forward along said drawing track to a position at which the blank is released from the die and carriage and drops down away from them, an elevator for raising the released carriage from said drawing track to the front end of the return track, the upper reach of said endless means being adapted to return the carriage along the return track, an elevator for lowering the returned carriage from the rear end of the return track to blank-gripping position in front of the die, means for tilting the rear elevator longitudinally to align it with the inclined rear end of the return track, and releasable means for holding the rear elevator against tilting in front of the die while the carriage is being removed from the elevator.

8. A draw-bench comprising a blank-gripping carriage adapted to be positioned in front of a die, an endless chain extending forward away from the die and having a lower strand for detachably engaging the carriage from above to move it with a gripped blank forward away from the die to a position at which the blank is released from the die and carriage and drops down away from them, a return track above the upper strand of said chain, means for elevating the released carriage from said lower strand to the front end of said track, the upper strand of the chain being adapted to return the carriage along said track, said upper strand having a forward section that sags out of engagement with the carriage, manually controlled means for selectively stopping the carriage on the upper track above said sagging chain section, and means for lowering the returned carriage from the rear end of the return track to blank-gripping position in front of the die.

9. A draw-bench comprising a blank-gripping carriage adapted to be positioned in front of a die, endless traveling means extending forward away from the die and having a lower reach, said carriage being provided with a vertically swingable connecting member adapted to be detachably engaged from above by said lower reach to move the carriage with a gripped blank forward away from the die to a position at which the blank is released from the die and carriage and drops down away from them, the pivoted connection of said member to the carriage body being substantially on a level with said lower reach while the carriage is being moved forward, a return track above the upper reach of said means, means for elevating the released carriage from said lower reach to the front end of said track, and means for lowering the carriage from the rear end of the return track to blank-gripping position in front of the die.

10. A draw-bench comprising a blank-gripping carriage adapted to be positioned in front of a die, a track extending forward from the die and having a pair of laterally spaced rails, an endless chain having a lower strand extending along the track between said rails and adapted to pull the carriage with a gripped blank forward along the rails to a position at which the blank is released from the die and carriage and drops down away from them, a return track above the upper strand of said chain, means for elevating the released carriage from said lower strand to the front end of said return track, the upper strand of the chain being adapted to return the carriage along said return track, and means for lowering the returned carriage from the rear end

of the return track to blank-gripping position in front of the die.

11. A draw-bench comprising a blank-gripping carriage adapted to be positioned in front of a die, means above the carriage for detachably engaging it to move it with a gripped blank forward away from the die to a position at which the blank is released from the die and carriage and drops down away from them, a return track, means for transferring the released carriage from said carriage-engaging means to the front end of said track, and means for transferring the carriage from the rear end of the track to blank-gripping position in front of the die.

12. A draw-bench comprising a die, a support for the die, a track connected to the front of said support and extending forward away from it, a blank-gripping carriage adapted to be positioned on the track in front of the die, an end-

less chain extending forward away from the die and having a lower strand for detachably engaging the carriage from above to move it with a gripped blank forward along the track away from the die to a position at which the blank is released from the die and carriage and drops down away from them, a drive sprocket for the chain adjacent the front end of the track and connected thereto, a return track above the upper strand of said chain, means for elevating the released carriage from said lower strand to the front end of said track, the upper strand of the chain being adapted to return the carriage along said track, and means for lowering the returned carriage from the rear end of the return track to blank-gripping position in front of the die.

EARL KNUDSEN,
HOWARD H. TALBOT.
